(57) **CLAIM**

The ornamental design for decking, as shown and described.

DESCRIPTION

FIG. 1 is a top plan view of decking according to the present invention;

FIG. 2 is a side view of the decking of FIG. 1, all other side views being the same; and,

FIG. 3 is a bottom view of the decking of FIGS. 1 and 2.

The broken lines shown in the Figures, including the details shown in FIG. 3, are for environmental purposes only and form no part of the claimed design.
